WORKPIECE-SHIFTING MEANS FOR USE WITH FORGING PRESSES

Karl Lichtenfeld, Neumark-Geiseltal, Germany, assignor to Veb Leuna-Werke Walter Ulbricht, Leuna (Kreis Merseburg), Germany

Application October 21, 1954, Serial No. 463,741

9 Claims. (Cl. 78—98)

This invention relates to forging presses, and more particularly to a device for turning the work in a forging press.

The turning over of the work is necessary for obtaining a satisfactory forging of the work. Works or forgings of small size may be readily turned over by hand. Works or forgings of large size, however, must be turned over by means of mechanical devices.

An object of the invention is to provide a device for the turning over of forgings in a forging press which may be readily manufactured at low costs.

Another object of the invention is to provide a device for the turning over of forgings in a forging press which does not obstruct freedom of manipulation on the forging press.

A further object of the invention is to provide a device for the turning over of forgings in a forging press which does not require a large additional space.

Another object of the invention is to provide a device for the turning over of forgings in a forging press which does not comprise a delicate mechanism and, therefore, is reliable in operation under the rough and dusty conditions of a forge.

A further object of the invention is to provide a device for the turning over of forgings in a forging press by means of which the output of a forging press may be considerably increased without major changes in the construction of the forging press and without the necessity of procuring new equipment.

Another object of the invention is to provide a device for turning over forgings in a forging press which does not require special driving devices or motors.

A further object of the invention is to provide a device for turning over forgings in a forging press which may be readily manufactured in the forge itself from means available to the forge and the maintenance whereof can be readily carried out by the management of the forge.

Other objects and structural details of the invention will be apparent from the following description when read in conjunction with the accompanying drawings, wherein:

Fig. 1 is a front elevational view of a forging press equipped with a turning device according to the invention,

Fig. 2 is a side elevational view of the forging press and turning device shown in Fig. 1, and

Fig. 3 is a front elevational view, on an enlarged scale, of a portion of the turning device shown in Fig. 1.

Referring now to Figs. 1 and 2, 10 generally indicates the support of the forging press. The cross-head 1 carrying the so-called top swage 2 is reciprocably mounted on said support 10. A work 4 to be forged, for example a shaft, rests on the bottom swage or anvil 3. The free end of the work 4 is suspended from the hook 11 of a forge crane (not shown) by means of an endless chain 3.

The turning device according to the invention comprises two pairs of chains or like flexible carrier means 5 and 5a, each pair of chains being suspended from the cross-head 1 of the forging press by means of hooks 12 and 12a respectively loosely engaged with said cross-head

1 and connected with one end of the chains. The other end of each chain 5 and of each chain 5a respectively is connected with a shackle 6 or 6a respectively. Each shackle 6 or 6a is in the shape of a bar having a plurality of inclined notches 13 and 13a respectively.

5 A first cross-bar or rigid beam 7 carrying pins 9 and 9a at its ends is associated with right hand set (as viewed in Fig. 2) of shackles 6 (6a) and a second cross-bar or rigid beam 7', likewise carrying pins 9 (9a) at its ends, 10 is associated with the left hand set (as viewed in Fig. 2) of shackles 6 (6a).

As best shown in Figs. 1 and 3, the portion 14 of the upper edge of the cross-bar 7 (and of course also of the cross-bar 7') is serrated or roughened in any suitable 15 manner. The pins 9 and 9a of the cross-bars 7 and 7' may be engaged with selected notches 13 and 13a of the shackles, so that the cross-bars are carried by the shackles 6 and 6a in a predetermined inclined position. The vari- 20 out notches 13, 13a cooperating with the pins 9, 9a permit an adjustment of the cross-bars 7, 7' at a predetermined height in dependence on the diameter of the work 4 and in an inclined position at a predetermined angle to the horizontal plane.

The operation of the device is as follows: 25 After the work has been taken out from the heating furnace by suitable means, it is run up under the press by means of a movable carriage (not shown). The movable cross-head 1 carrying the top swage 2 is lowered to such an extent that the work is tightly gripped. Then the two cross-bars 7 and 7' are engaged with notches 13, 13a of the shackles 6, 6a by means of their pins 9, 9a. Now, when the cross-head 1 is raised, the two cross-bars 7, 7' will lift the work 4. By shifting the carriage in the direction of the arrow A (Fig. 2) or by drawing the cross-bars 7, 7' in the direction of the longitudinal axis of the work 4, that section of the latter which is to be forged can be brought into register with the anvil 3. Then, the cross-head 1 is lowered and the first forging stroke is made. During the forging, the cross-bars 7, 7' 30 are suspended freely under the work 4. Then, the operator displaces the inclined cross-bars 7, 7' sidewise from their normal freely suspended position, substantially in the direction of their longitudinal axes, into the position shown in Fig. 1, wherein the left hand chain 5 is some- 35 what inclined to the vertical line and the serrated edge 14 of the cross bar 7 is engaged with the work 4. This lateral displacement of the cross-bars 7, 7' may be readily carried out manually by means of a rod or tube 15 (see Fig. 1) having a length of approximately 3 meters. For 40 this purpose the rod 15 is pushed in the direction of the arrow A. Thus, upon a subsequent lifting of the cross-head 1 the upper edges of the cross-bars 7, 7' cause a lifting of the work 4 and owing to the inclined position of the chains 5, 5a and of the cross-bars 7, 7' the work 4 45 is simultaneously turned around its longitudinal axis in the direction of the arrow B. The more the cross-bars 7, 7' are laterally displaced from their normal position, the greater the angle of turn, which may amount to as much as 360°. However, for normal forging operations turning angles up to at most 60° suffice, so that small displace- 50 ments of the cross-bars 7, 7' suffice to turn the work 4.

The turning device according to the invention affords still further advantages. Thus it may be employed to forge long shafts. For this purpose the center portion of 55 the block to be forged is first reduced to the desired diameter. During this operation the work is turned about its longitudinal axis, and gradually shifted axially of itself. For this purpose, the cross-bar arranged at the side of this end is pulled outwardly, away from the anvil, by means of a hook. Now, when the cross-head is 60 raised, the cross-bar hanging in an outwardly inclined direction drags the work in the desired direction. This 65

shifting of the work in the direction of the arrow C is assisted by an appropriate travel of the crane holding the long free end of the work in the endless chain 8.

The turning of the work is assured by the serrated or roughened portion 14 of the cross-bars 7, 7'. When the teeth of the serrations are rather small it is also possible to turn materials of square, hexagonal or other polygonal cross-sections, since the small teeth will securely engage the material in any position. The inclination of the cross-bars, depending on the desired angle of rotation, is between 10° and 25°.

I have described a preferred embodiment of my invention, but it is understood that this disclosure is for the purpose of illustration and that various omissions or changes in shape, proportion and arrangements of parts, as well as the substitution of equivalent elements for those, herein shown and described may be made without departing from the spirit and scope of the invention as set forth in the appended claims.

For example, instead of two pairs of chains, each pair carrying a cross-bar at each side of the anvil, only one pair of chains carrying a single cross-bar could be arranged at one side of the anvil.

What I claim is:

1. A workpiece-displacing device for use in connection with a forging press, comprising a vertically reciprocable element, means for mounting said element for vertical reciprocation, means for supporting said work-piece, beam mounting means, rigid beam means arranged below said work piece and connected to said beam mounting means to position said beam means at an angle to the horizontal, and means connecting said beam mounting means and said element to support said beam from said reciprocable element, whereby raising of said element brings said beam into contact with the work piece to lift the latter and displace it to present a different surface portion to said reciprocable element.

2. A workpiece-displacing device for use in connection with a forging press or the like, comprising a vertically reciprocable element, means for mounting said element for vertical reciprocation, work-piece supporting means, a rigid beam, and means to support said beam from said reciprocable element below said work piece and at an angle to the horizontal, whereby raising of said element brings said beam into contact with the work piece to lift said work piece and rotatably displace the same.

3. A device according to claim 1, further comprising cooperable means on both said beam means and said mounting means for adjusting the inclination of said beam means relative to the horizontal, whereby the extent of displacement of said workpiece on said beam means may be varied.

4. A device according to claim 2, said beam means being roughened at the part thereof engageable with said workpiece, whereby slippage of the latter on said beam means is substantially inhibited.

5. A device according to claim 4, said beam means comprising at least one elongated rigid beam, said mounting means comprising a pair of shackles connected to said beam at respective locations spaced from one another longitudinally of said beam, and said carrier means comprising a pair of chains connected to said shackles, respectively.

6. A device according to claim 5, further comprising cooperable means on both said beam and said shackles for adjusting the inclination of said beam relative to the horizontal, said cooperable means comprising at least two pins extending laterally from said beam at said spaced locations, respectively, and a plurality of slots provided in each of said shackles for selectively receiving said pins, whereby the extent of displacement of said workpiece during each lifting thereof by said beam is predetermined.

7. A device usable in connection with the reciprocally movable ram means of a forging press for rotating an elongated round workpiece and for shifting the same longitudinally of itself, comprising rigid beam means adapted for location below said workpiece and engageable with the latter from below the same, mounting means supporting said beam means so as to dispose the workpiece-engaging part of the latter obliquely with respect to the horizontal, and flexible carrier means supporting said mounting means for displacement thereof and thus of said beam means from a normal position substantially transversely to and longitudinally of said workpiece and constructed for vertical reciprocal movement in response to operation of said ram means, to thereby raise and lower said mounting means and bring said beam means into and out of lifting engagement with said workpiece, respectively, upon movement of said ram means out of and into forging relation to said workpiece, whereby said workpiece when lifted by said beam means upon displacement of the latter transversely to said workpiece is enabled to rotate relative to and on said beam means during return thereof to said normal position, while upon displacement of said beam means longitudinally of said workpiece, the latter when lifted by said beam means is displaced longitudinally of itself during return of said beam means to said normal position thereof.

8. A device according to claim 7, further comprising cooperable pin and slot means on said beam means and said mounting means for adjusting the degree of obliquity of said beam means relative to the horizontal, whereby the extent of rotation of said workpiece during each lifting thereof by said beam means upon transverse displacement of the latter is predetermined.

9. A device according to claim 8, said beam means being serrated at the part thereof engageable with said workpiece, whereby slippage of the latter on said beam means is substantially inhibited.
